UNITED STATES PATENT OFFICE.

STEPHEN G. SMITH, OF HANNIBAL, MISSOURI.

AIR-DIFFUSER.

SPECIFICATION forming part of Letters Patent No. 701,228, dated May 27, 1902.

Application filed November 25, 1901. Serial No. 83,607. (No model.)

To all whom it may concern:

Be it known that I, STEPHEN G. SMITH, a citizen of the United States, residing at Hannibal, in the county of Marion and State of Missouri, have invented certain new and useful Improvements in Air-Diffusers; and I do hereby declare the following to be a full, clear, and exact description of the invention, such as will enable others skilled in the art to which it appertains to make and use the same.

My invention relates to improvements in air-diffusers; and the object of the invention is to deflect or spread a current of air directed thereagainst, so as to cause diffusion of the air in all directions.

Heretofore a current of air induced by an ordinary rotary fan scarcely spreads beyond the circumferential limits of the fan. Such a blast or jet of air confined to a direct or limited path is too strong for comfort and does not tend to cool the atmosphere of a room. The effects resulting from being in a draft of such force are liable to be very injurious.

Previously devices have been provided for partly diffusing a current of air; but never has the diffusion been wholly accomplished.

My device is intended to overcome the objections to the use of a rotary fan giving a direct blast and to provide for the thorough diffusion of all the air within a room.

Broadly, my invention consists of a series of deflecting-blades arranged one within the other of such construction that they will be capable of spreading a current of air in all directions. Said blades are suitably held in their respective arrangement, and means may be provided for attaching the device to the guard of an ordinary electric fan.

In the accompanying drawings, illustrating the preferred embodiment of my invention, Figure 1 is an elevation of my device applied to the guard of an ordinary electric fan. Fig. 2 is a cross-section thereof.

In carrying out my invention I provide a series of deflecting-blades 1, arranged one within another. Preferably these blades are circular and arranged concentrically within each other. Cross-pieces 2 are suitably connected to the blades, preferably by soldering, for holding them in their respective places. In the drawings are shown two cross pieces

or wires placed at substantially right angles to each other upon opposite edges of the 55 blades, and for attaching the devices to the guard of an ordinary electric fan I provide hooks 3 3 3 3, preferably connected to the outer blades at diametrically opposite points. These hooks are preferably constructed of 60 spring metal in substantially the form shown, and for convenience in connecting the hooks to a guard those diametrically opposite are faced in the same direction.

By using my device a current of air contacting therewith will be spread in all directions. This will cause diffusion of all the air in a room and obviate the necessity of a person being out of the direction of the fan for fear of injurious effects. Moreover, the air 70 in the room will be cooled wherever the diffusion has taken place and not along a defined path, as in the case of the ordinary rotary fan.

It will be observed that a device constructed according to my invention will occupy but a limited space, will be durable, and cheap of manufacture.

I am aware that changes in the form and construction of the parts herein shown as the 80 preferred embodiment of my invention may be made without departing from the principles or sacrificing the advantages thereof, and I therefore reserve the right to make such changes as fairly fall within the scope of my 85 invention.

Having thus described my invention, what I claim as new, and desire to secure by Letters Patent, is—

1. In an article of the character described, 90 placed upon the delivery side of a fan, a series of deflecting-blades arranged concentrically one within another, and means for connecting said blades.

2. In an article of the character described, 95 placed upon the delivery side of a fan, a series of deflecting-blades arranged concentrically one within another and slanting outwardly, and means for connecting said blades.

In testimony whereof I affix my signature 100 in presence of two witnesses.

STEPHEN G. SMITH.
